United States Patent Office

Des. 197,845
Patented Mar. 31, 1964

197,845

FLOOR TILE

Eugene E. Parson, 2803 Harding Blvd., Granite City, Ill.

Filed Jan. 24, 1963, Ser. No. 73,300

Term of patent 14 years

(Cl. D18—2)

FIG. 1

I claim:

The ornamental design for a floor tile, substantially as shown.
